UNITED STATES PATENT OFFICE.

JOHANNES F. H. MARTINSEN, OF CHICAGO, ILLINOIS.

ROLLER-SKATE.

No. 893,341.

Specification of Letters Patent.

Patented July 14, 1908.

Application filed March 9, 1908. Serial No. 419,914.

To all whom it may concern:

Be it known that I, JOHANNES F. H. MARTINSEN, a citizen of the United States, residing at Chicago, in the county of Cook and 5 State of Illinois, have invented a certain new and useful Improvement in Roller-Skates, of which the following is a specification.

My invention relates to roller skates, and the object of the invention is to provide 10 means to yieldingly support the foot of the skater and to permit the rocking movement which is possible in ice skating.

I obtain my object by the mechanism illustrated in the accompanying drawings, in 15 which:

Figure 1 is a side view of a skate embodying my invention. Fig. 2 is a plan sectional view thereof taken on the line 2—2 of Fig. 1. Fig. 3 is a transverse sectional elevation 20 taken on the line 3—3 of Fig. 1, and Fig. 4 is a perspective view of a portion of the foot rest.

Similar numerals refer to similar parts throughout the several views.

25 The truck 10 is supported upon the rollers 11 and consists preferably of a single piece of sheet steel lying, in the main, horizontally, but having lateral depending flanges 10^a with extensions 10^b adapted to support the 30 axles 12. The foot rest 13 is provided with suitable means of attachment to the foot of the user. In the present instance these attaching means consist of a heel plate 14 having a heel strap 15 and a toe plate 16 having 35 a toe strap 17. These attaching means may assume any desirable form.

In its simplest and best form the foot rest 13 consists of a plate adapted, in the main, to lie horizontally above the truck 10, and is 40 provided with lateral depending stiffening flanges 13^a with extensions 13^b and 13^c at the front and rear respectively. A spring 18 which is preferably of a length approximately equal to the length of the truck is secured at 45 its middle to the middle of said truck. The preferred means of attachment are the rivets 19, which are located one in front of the other in order to hold the middle portion of the spring firmly and rigidly to the truck. The ends of 50 the spring extend upwardly from the middle portion, and are attached at the front and rear ends to the extensions 13^b and 13^c re-

spectively. In the preferred form of attachment, eyes 18^a are formed at the extremities of the spring, and these inclose bolts 20. 55 One of these bolts is rigidly fastened to the extension 13^c and the other is slidably mounted in the horizontal slot 13^d in the extension 13^b. This affords the requisite play between the parts and permits the spring 60 to expand and contract as the footrest falls and rises relatively to the truck.

When the skate is in use, the footrest may yield downwardly without departing from horizontal position, or it may be tilted backwards or forward, as a result of which the sensation to the skater will be similar to that when using ice skates. This construction has the advantage, however, of giving more yielding support to the skater than ordinarily occurs in using ice skates. The spring 70 absorbs all ordinary jar due to the inequalities in the surface skated over and gives a smoothness in running which greatly adds to the pleasure of its use. A heavy or light 75 spring will be employed depending upon the weight of the person who is to use it.

Having thus described my invention, what I claim as new, and desire to secure by Letters Patent, is:

1. In a roller skate, a truck provided with rollers, a footrest having means of attachment to the foot of the wearer, a spring rigidly fastened to the middle portion of the truck, a pivoted connection between one end 85 of the spring and the corresponding end of the truck and a sliding connection between the other end of the spring and corresponding end of the truck.

2. In a roller skate, the combination of a 90 truck provided with rollers, a footrest having means of attachment to the foot of the wearer, a spring rigidly fastened to the middle portion of the truck and articulate connection between the rear end of the spring 95 and the rear end of the footrest and a sliding connection between the forward end of the spring and the forward end of the footrest.

3. In a roller skate, two parallel rigid members, the lower one mounted on rollers 100 and the upper one adapted to be secured to the foot of the user, the upper member having lateral depending flanges horizontally slotted, a strip of spring metal rigidly fas-

tened in the middle to the lower of said members and at its ends connected to the upper of said members, one of said connections including a bolt held by said spring and penetrating the slots in the flanges of said upper member.

5 In witness whereof, I have hereunto sub-

scribed my name in the presence of two witnesses.

JOHANNES F. H. MARTINSEN.
